H. E. DREWS,
SAFETY HOISTING HOOK,
FILED APR. 26, 1922.

Inventor:
Hugo Ernest Drews,
By David W. Cardwell
Attorney.

UNITED STATES PATENT OFFICE.

HUGO ERNEST DREWS, OF JERSEY CITY, NEW JERSEY, ASSIGNOR OF ONE-HALF TO
HERMAN F. KIESEWETTER, OF JERSEY CITY, NEW JERSEY, AND ONE-HALF TO
LELAND STANFORD.

SAFETY HOISTING HOOK.

Application filed April 26, 1922. Serial No. 556,604.

To all whom it may concern:

Be it known that I, HUGO ERNEST DREWS, a subject of the King of Denmark, having declared my intentions of becoming a citizen of the United States, residing in Jersey City, Hudson County, and State of New Jersey, have invented certain new and useful Improvements in Safety Hoisting Hooks, of which the following is a specification.

My invention relates to that class of hooks which are used in hoisting packages, bales &c., from the holds or hatches of steamships, in which the rope or cable is attached to the upper or eye end of the hook, the other end of the rope or cable passing around a drum or windlass or other form of hoisting apparatus.

Heretofore accidents and loss of life have been caused by the packages falling off the end of the hook, by reason of the hook catching in some object or for other reasons of the rope or cable becoming detached from the eye of the hook, and it is the object of my invention to guard and overcome these objectionable features by providing a hook which is free of all projections on its surface, having a smooth and plain surface, and to guard against all possibility of the package becoming detached from the hook when placed thereon.

My invention consists broadly in forming a hook in two sections, which are mounted slidably upon each other, the upper end of one section forming an eye for engaging a rope or cable, the other end forming a hook for engaging the sling for holding the package to be hoisted; and in providing means whereby the two sections are locked positively together and held in this position until released by the operator.

The invention also includes minor details of construction hereinafter described and claimed.

In the accompanying drawings,

Fig. 1, is a side elevation of my improved hook, showing the same attached to one end of a rope and the other end engaging a sling on a bale;

Fig. 2, a side elevation of my hook, the parts being shown in a locked position;

Fig. 3 a similar view, the sections being shown as spread apart, and the middle portion of one section being broken away to

more clearly show one of the slots, and the means of connecting the two sections;

Fig. 4, is an edge view taken in the direction of the arrow Fig. 2;

Figs. 5 and 6, edge views of the two sections, showing the straps spread apart to allow the insertion of the sections in the slots before the straps are welded to the sides of their respective sections.

The hook H, as a whole is formed of the two sections A, B.

The section A, is formed at its upper end with an eye a, for engaging a ring r, in the rope or cable R, and to insure the cable or rope being held in place, a spring s, fastened at a', to the section A, and free at its other end to permit of the insertion of the cable or rope R, is provided. It is obvious that a bolt and nut may be provided with like effect, the bolt passing through the eye a, and held in position by a nut on its outer end

The upper end of the section A, is formed with a recess a², and the lower end A², with a catch hook a'', the purpose of which will be more fully explained.

The section A, at or near its upper end and at a prescribed distance below the eye a, is formed with an elongated slot a³, having the shoulders a, a⁴, for limiting the extent of motion of the section B.

The section B, is formed at its upper end with a catch hook b, which engages the recess a², formed in the section A, when the two sections are brought together, and with an elongated slot b², and shoulders b³, b⁴, which limit the extent of motion of the section A, when in position. The hook B', is formed at its lower end with a recess b', with which the catch hook a'', on the section A, engages when the parts are brought together locking the two sections positively with relation to each other, in which position they will remain until released by the operator.

The sections A, B, are preferably made of metal and are "dropped forged". The slots a³, b², are formed by drilling or punching out the metal at the desired point, the straps a⁴⁴, b⁴⁴, being cut and forming openings a³³, b³³, (as shown in Figs. 5 and 6) to allow of the insertion of the section A, in place, before the straps a⁴⁴, b⁴⁴, are welded onto the sides of the sections A, B.

When it is desired to insert the lower end

22
 of the hook B', in a sling of a package, the section B, is disengaged from the section A, by raising said section B, upward, sliding the same within the slot a², in the section A, 5 and allowing said hook portion B', to open as far as required, when the sections are again locked together by pressing the lower section A², of section A, with its catch hook a'', into engagement with the recess b', in 10 the lower end of the loop B', and at the same time engaging the catch hook b, with the recess a², formed in the upper end of the section A.

It will thus be seen that I provide a safety 15 hoisting hook, that is positive in action, in that the more strain applied to the lower loop B', the tighter the parts will be locked together, and at the same time by my construction make a hook as a whole that is free 20 of all projections that are liable to catch or interfere with the operation of hoisting, and thereby prevent the possibility of the package becoming detached from the hook.

What I claim as my invention and desire 25 to secure by Letters Patent is,

1. A safety hoisting hook of the character designated, formed in two sections, one sec-

tion having an eye and the other section formed with a hook portion, said sections being mounted loosely upon and held within each other near their upper extremities substantially as described, each of said sections being formed with a recess and catch hook for engagement with each other, for the purpose described. 30
35

2. A safety hoisting hook of the character designated, formed in two sections, one section having an eye provided with means for holding a rope or cable therein, the other section being formed with a hook portion, both of said sections being formed with slots 40 therein whereby the said sections are mounted slidably upon each other, said slots being formed with shoulders for limiting the extent of motion of said sections, and each of said sections being formed with recesses and catch hooks for the purpose of locking said sections together, for the purpose and substantially in the manner described. 45

HUGO ERNEST DREWS.
